UNITED STATES PATENT OFFICE

118,978

DESIGN FOR A FINGER RING

Felix P. Kinsley, St. Louis, Mo.

Application October 26, 1939, Serial No. 87,871

Term of patent 14 years

To all whom it may concern:

Be it known that I, Felix P. Kinsley, a citizen of the United States, residing at the city of St. Louis, State of Missouri, have invented a new, original, and ornamental Design for a Finger Ring, of which the following is a specification, reference being had to the accompanying drawing, forming part thereof.

Fig. 1 is a top view of a finger ring showing my new design; and

Fig. 2 is a side view thereof.

The essential features of my design reside in the mounting shown in full lines.

I claim:

The ornamental design for a finger ring, as shown and described.

FELIX P. KINSLEY.
